UNITED STATES PATENT OFFICE.

ROBERT S. KEARNEY, OF NEW YORK, N. Y.

SPARK-PLUG GUARD.

No. 897,466.

Specification of Letters Patent.

Patented Sept. 1, 1908.

Application filed April 9, 1907. Serial No. 367,146.

To all whom it may concern:

Be it known that I, ROBERT S. KEARNEY, citizen of the United States, residing at New York, in the county of New York and State of New York, have invented certain new and useful Improvements in Spark-Plug Guards, of which the following is a specification.

This invention relates to protecting means for inclosing an otherwise exposed spark plug for the purpose of minimizing its fragility, overcoming the tendency of the electric current to short circuit and the plug to crack upon contact with spray, rain or moisture of any description, and furnish a complete protection from blows of tools used about an engine, oars, poles and other paraphernalia in use about a boat or vehicle equipped with an explosive engine.

A further purpose of the invention is to provide a guard which may remain attached to the plug to protect the same when disconnected from the engine and when in position will add to the appearance of the engine rather than detract from the looks thereof.

For a full description of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a side elevation of a spark plug having the improved guard applied thereto. Fig. 2 is a sectional view thereof. Fig. 3 is a detail perspective view of an end portion of the body of the guard. Fig. 4 is a detail perspective view of the cap inverted.

Corresponding and like parts are referred to in the following description and indicated in all the views of the drawings by the same reference characters.

The spark plug 1 may be of any pattern or make and is provided with a coupling 2 by means of which it is connected to the engine. In accordance with this invention the coupling 2 is provided upon its outer side with a threaded portion 3 exterior to the flange 4 to which the staple, wrench or like tool is fitted when screwing the coupling home or un-

screwing the same from the engine or like part to which the spark plug is fitted.

The guard comprises the body 5 and cap 6. The body 5 is hollow and consists of a cylindrical shell or casing the lower end being internally threaded to make a screw thread connection with the part 3 of the coupling 2. The cap 6 is of rounded form and is hinged to the body at 7 and when closed is secured by means of a catch 8. The hinge 7 is of such construction as to be practically invisible and not to offer any projection which would detract from the appearance of the guard and be in the way. The hinge is formed of a projection 9 of the cap adapted to fit into a notch 10 in the upper edge of the body, a pin passing through the overlapped parts to pivotally connect them. The catch 8 is an integral part of the cap and projects therefrom and is adapted to enter a depression 11 in a side of the body 5 near the upper end thereof. The projection 8 and depression 11 are such as to admit of the catch coming about flush with the outer surface of the guard. The catch is located by preference diametrically opposite to the hinge joint. A notch 12 is formed in the upper edge of the body 5 to receive the conductor 13 by means of which the current is conveyed to the spark plug. To prevent rain, spray or other foreign matter from entering the notch 12 a projection or hood 14 extends from the cap 6 and forms a protector to cover the said notch. The pendent hook 14 curves outward and downward and is of such relative proportions as to conform to the shape and contour of the conductor 13 and form a covering which will shed moisture or any other matter tending to enter the notch 12.

The plug may be detached from the engine without necessitating the removal of the guard, hence is protected at all times from injury. It is also apparent that the guard may be removed at any time for any purpose or that access may be had to the plug without necessitating the removal of the guard the cap being released and drawn up out of the way upon its hinge or pivotal connection with the body 5. By forming the guard of metal such as brass or copper it may be polished and will add to the appearance of the engine, while at the same time protect the spark plug from injury either from knocks or from moisture coming in contact therewith.

Having thus described the invention, what is claimed as new is:

1. A guard for spark plugs comprising a cylindrical shell open at both ends and adapted to slip over the spark plug and inclose the same, one end of the shell being secured to the base of the spark plug while the opposite end is provided with a notch, a cap hinged to the notched end of the cylindrical shell, a catch for holding the cap normally in a closed position, and a pendant hood carried by the cap and projecting over the notch.
- 10 2. A guard for spark plugs comprising a cylindrical shell open at both ends and adapted to slip over the spark plug and in-

close the same, one end of the shell being detachably secured to the base of the spark plug while the opposite end is provided with a notch, a cap hinged to the notched end of the cylindrical shell, a catch for holding the cap normally in a closed position, and a pendant hood carried by the cap and projecting over the notch. 15 20

In testimony whereof I affix my signature in presence of two witnesses.
